DESIGN FOR A COMBINED GRAVE PROTECTOR AND MARKER

Ford A. Caperton, Vernon, Tex.

Application October 29, 1940, Serial No. 96,167

Term of patent 7 years

To all whom it may concern:

Be it known that I, Ford A. Caperton, a citizen of the United States, residing at Vernon, in the county of Wilbarger and State of Texas, have invented a new, original, and ornamental Design for a Combined Grave Protector and Marker, of which the following is a specification, reference being had to the accompanying drawing, forming part thereof.

In the drawing:

protector and marker, showing my new design.

I claim:

The ornamental design for a combined grave protector and marker, substantially as shown.

FORD A. CAPERTON,
